DOOR-OPERATING MECHANISM

Ralph H. Greigor, Columbus, Ohio, assignor to
The Kinnear Mfg. Company, Columbus, Ohio,
a corporation of Ohio

Application September 4, 1934, Serial No. 742,534

14 Claims. (Cl. 20—20)

This invention relates to improvements in door-operating mechanism, and has for its object to provide an improved means or instrumentalities for preventing the accidental closing 5 of a door, particularly a vertically moving door.

It is an object of this invention to provide, in connection with a door formed of a plurality of relatively movable sections, means to successively move the sections, and means to prevent 10 the accidental and unintentional closing of the door sections.

It is also an object of the invention to provide a door-operating mechanism for operating a door composed of sections, and in which the sections 15 are successively moved for opening a passageway closed by the door, and on one of which sections is means for automatically preventing the accidental and unintentional closing of the door.

These and other objects and advantages will 20 appear from the following description taken in connection with the drawings.

Referring to the drawings:

Figure 1 is an inside elevation of the door, with 25 part of the supporting structure for the door shown in section.

Figure 2 is a section on the line 2—2 of Figure 1.

Figure 3 is a section on the line 3—3 of Figure 1.

Figure 4 is a section on the line 4—4 of Figure 3.

The door operating mechanism, the subject of the invention, is adapted to be used with doors of various forms, particularly vertically movable 35 doors and doors formed of sections. In the present instance the mechanism is used in connection with a door composed of two sections, slideable with relation to each other and guided by suitable instrumentalities provided therefor on spaced 40 hollow columns 1. These columns may form the jambs of walls, or they may be used independently of any wall structure. In the present instance the columns are supported on the decks of pier sheds used for housing and storing various articles, or for other desired purposes.

Each column has one or more jambs 2, to which a plate 3 is attached at one edge. To the other edge of this plate is attached one arm of an angle iron 4. There is also provided on each column, 50 spaced from the angle iron 4, an I-beam 5. This I-beam is especially used when a column is used in conjunction with two doors. The tops of two columns forming a passageway closed by a door are connected by means of a transversely extending, vertically disposed plate 6. Extending

inwardly from the upper end of each member 5 is a horizontally disposed beam 7, braced by means of a brace member 8 extending from the beam to the member 5. The lower ends of the columns rest upon a deck floor 9, while at the upper ends of these columns is an overhead structure 10.

The door for closing the passageway formed by two adjacent columns is formed of two sections, a lower section 11 and an upper section 12. At the bottom of the lower section and at each side 10 thereof is a casting 13 attached to a lateral channel member 15. Each edge of the door has thereon an angle iron 14, which has one arm in engagement with the channel member 15 and the other arm spaced from the edge of the door to 15 provide a groove into which one arm of the angle iron 4 extends. The casting 13 has thereon a bearing 16 in which a pin 17 works. There is also a casting 18 which has extending therefrom two arms 19, with holes therein to receive the 20 pin 17. These arms engage opposite ends of the bearing 16.

The casting 18 has thereon a laterally extending arm 20, which has projecting therefrom at right angles a fixed jaw 21. The casting 18 has 25 extending upwardly therefrom a pair of spaced members 22, between which a lever 23 is pivotally mounted intermediate its ends upon a pivot pin 24. On one end of the lever 23 is a cam 25 which forms a jaw cooperating with the jaw 21 to grip 30 one arm 26 of an angle iron, which has another arm 27 attached to the standard. The arm 26 forms a flange which is one element of the door supporting mechanism. The arm 27 forms a trackway and part of a guide channel for a roller 35 28 located on one end of the pin 17.

Cooperating with the arm 27 to form the channel for guiding the roller 28 is the member 5. On the end of the pin 17 remote from the roller 28 is a roller 29, adapted to engage a track 30 40 formed on the standard. The rollers 28 and 29 serve as guide rollers and anti-friction means to guide the door as it opens and closes.

The end of the lever 23 remote from the cam jaw 25 has attached thereto one end of a chain 45 31 by means of a pin 32. This chain passes upwardly and over a sprocket 33 located on a shaft 34, suitably supported at the upper end of a standard. After passing over the sprocket 33 the chain passes beneath and about a pulley 35 50 located upon the upper end of a counter-balance weight 36, and extends upwardly and is attached to some suitable attaching means 37. A shaft 38 is connected at one end by means of a worm and gear mechanism located in a box 39 to the 55

shaft 34 for rotating the shaft and the sprocket wheels thereon. The chain, sprocket and pulley mechanisms are arranged in pairs, one at each edge of the door, while there is only one shaft 5 38 for rotating the shaft 34. The shaft 38 is rotated by means of a sprocket 40 on a shaft 40a, connected to the shaft by bevel gears in a box 38a. Around the sprocket 40 is a chain 41 by which the sprocket is rotated for rotating the shaft 34.

10 At each edge and at the top of the lower door section is a roller 42 adapted to engage a guide member 43 located on the member 5. This roller is also used for guiding the upper end of the door 15 onto a trackway used for supporting and guiding the door when in elevated position. Adjacent each roller 42 is a bevel faced lug 44. A cam member 45 is pivoted on a pin 46 so that the cam member 45 may be adjusted and held by any 20 suitable means to properly engage the roller 42.

25 On the lower edge of the beam 7 is a horizontally disposed track 50 which extends inwardly from the standard. The end of this track adjacent the standard is arcuate, as indicated by the numeral 49. Above and spaced from the arcuate end of the track is an arcuate guide 47 formed as part of a supporting bracket 48. As the lower section of the door moves upwardly the upper end thereof, through the roller 42, is guided by 30 the cam 45 and the arcuate guide 47 onto the track 50.

35 On the upper end of the top section, at each edge, there is a dog 51 and a roller 52 adapted to travel along a track 53 formed on the upper edge 40 of the bracket 48. There is also provided on the upper edge of this bracket a ratchet which has therein a plurality of teeth 54 for engagement by the dog to hold the upper end of the door section close to the standards. Attached to the dog 45 and extending downwardly is an arm 55 adapted to be engaged by the lug 44 as the lower section of the door moves upwardly for elevating the upper section. The lug 44 first engages the lower end of the arm to release the dog from the ratchet 50 so that the upper section of the door may be moved. As the lower section of the door moves upwardly, with the lug 44 in engagement with the arm 55, the upper section is carried along with the lower section but resting on top of it so that the two are in superimposed position and supported upon the track 50 when the door is in open position.

55 When the door is closed the door sections and operating mechanism are substantially in the position shown in Figure 2. In this position the lower section of the door rests upon the decks of the sheds, or other supporting structure, while the upper section is supported by the rollers 52 above the upper ends of the plates 3. The door 60 at the point where the two sections come together is held against the standards by means of the rollers 42 and the guide and wedging members 43. The upper end of the upper section is held in closed position by means of the dogs 51 engaging the ratchet teeth 54.

65 In the event it is desired to open the door the chain 41 is operated to cause the shaft 34 to rotate and move the sprocket chains 31. The rotation of the shaft 34 first moves the lower section of the door upwardly. The rollers 42, as this section moves upwardly, pass over the cams 45, engage the arcuate part 47 of the brackets, and the tracks 50. After the rollers 70 42 or about the time that they have engaged the cam members 45, the lugs 44 engage the arms

55 to first release the dogs 51 and thereafter move the upper section of the door along with the lower section. The operation is continued until both sections are supported in horizontal position by the tracks 50.

5 In the event the sprocket chains 31 should break either during the opening or closing of the door, the cam jaw 25 will be forced into engagement with the members 26, thereby gripping these members through the cooperation of 10 the fixed jaws 21. For the purpose of urging the jaws 25 into cooperative relation with the jaws 21 for gripping the arms 26 for supporting the door, each jaw 25 is provided with a spring 15 56, tending to urge the cam jaw toward the fixed jaw. These jaws gripping the arms prevent the door from falling.

20 It will be noticed that the operating power is applied to the door through the levers 23, which have thereon the cam jaws. The application of lifting force to the door automatically releases the jaws, both fixed and pivoted, from the arms 26 but whenever one or more of the chains 31 are broken the corresponding jaw or 25 jaws will grip the arms 26.

25 It will be understood that I desire to comprehend within my invention such modifications as come within the scope of my claims and my invention.

Having thus full described my invention, what 30 I claim as new and desire to secure by Letters Patent, is:

1. In a door support and guide, a pin supported on the door, a member pivoted on the pin and having thereon a fixed jaw, a lever pivoted intermediate its ends on said member, said lever having on one end a cam jaw for cooperating with the fixed jaw, and a guide roller on the pin.

2. A door support and guide comprising a 40 member having thereon a pair of rollers and a pivoted clamp, said clamp comprising a fixed jaw and a movable jaw.

3. A door support and guide mechanism comprising a member having thereon a bearing, a 45 pin in the bearing, a roller on the pin, and a clamp pivoted on the pin.

4. A door support and guide mechanism comprising a member having thereon a bearing, a pin in the bearing, a roller on the pin, and a 50 clamp pivoted on the pin, said clamp consisting of a fixed jaw, a movable jaw and a spring tending to urge the movable jaw towards the fixed jaw.

5. A door support and guide mechanism comprising a member having thereon a bearing, a pin in the bearing, a casting having a pair of arms pivoted to the pin at the ends of the bearing, a roller on the pin adjacent each arm, and a clamp on the casting.

6. A door support and guide mechanism comprising a member having thereon a bearing, a pin in the bearing, a casting having a pair of arms pivoted to the pin at the ends of the bearing, a roller on the pin adjacent each arm, and a clamp on the casting, said clamp comprising a fixed jaw formed integral with the casting and a movable jaw cooperating with the fixed jaw.

7. A door support and guide mechanism comprising a member having thereon a bearing, a pin in the bearing, a casting having a pair of arms pivoted to the pin at the ends of the bearing, a roller on the pin adjacent each arm, and a clamp on the casting, said clamp consisting of 70 75

a fixed jaw formed integral with the casting, a lever pivoted intermediate its ends to the casting and having on one end a cam jaw cooperating with the fixed jaw, and a spring urging the 5 cam jaw towards the fixed jaw.

8. In a door-operating mechanism, in combination with a guide and a flange, a pin supported on the door, a roller on the pin for engagement with the guide, means pivotally mounted 10 on the pin to clamp the flange, said clamp means consisting of a fixed jaw, a movable jaw and a spring urging the movable jaw towards the fixed jaw, and means connected to the movable jaw and acting against the spring to move the door.

9. In a door-operating mechanism, in combination with a guide and a flange, a pin supported on the door, a roller on the pin for engagement with the guide, means pivotally mounted on the 20 pin to clamp the flange, said clamp means consisting of a fixed jaw, a movable jaw and a spring urging the movable jaw towards the fixed jaw, and means connected to the movable jaw and acting against the spring to move the door, said 25 last-named means comprising a chain and means acting on the chain.

10. In a door-operating mechanism, in combination with a guide and a flange, a pin supported on the door, a roller on the pin for engagement 30 with the guide, means pivotally mounted on the pin to clamp the flange, said clamp means consisting of a fixed jaw, a movable jaw and a spring urging the movable jaw towards the fixed jaw, and means connected to the movable jaw and acting 35 against the spring to move the door, said last-named means comprising a chain attached at one end to a fixed point and at its other end to the movable jaw, a sprocket over which the chain passes, a pulley on the chain, a weight supported

by the pulley, and means to rotate the sprocket.

11. In a door-operating mechanism, in combination with a guide and a flange, a member on the door, a pin on the member, a roller on each end of the pin for engaging the guide, a casting having arms pivotally mounted on the pin between the member and the rollers, a fixed jaw on the casting, a lever pivoted intermediate its ends to the casting, said lever having on one end a jaw cooperating with the fixed jaw to grip the 10 flange, means tending to urge the lever jaw toward the first jaw, and means attached to the other end of the lever to move the door and move the lever jaw away from the fixed jaw.

12. In a door-operating mechanism, in combination with a guideway having a flange therein, a door having a roller thereon in the guideway, door moving means, and means to connect the door-moving means to the door, said last-named means comprising gripping members within the 20 guideway to grip the flange.

13. In a door-operating mechanism, in combination with a guideway having a flange therein, a door having a roller thereon in the guideway, door-moving means, and means to connect 25 the door-moving means to the door, said last-named means comprising a fixed member and a movable serrated member in the guideway to grip the flange.

14. In a door-operating mechanism, in combination with a guideway having a flange therein, a door having a roller thereon in the guideway, means pivoted to the door to grip the flange, said 30 means comprising a fixed jaw and a lever pivoted intermediate its ends and having one end serrated to form a jaw cooperating with the fixed jaw to grip the flange, and door-moving means connected to the other end of the lever.

RALPH H. GREEGOR.
